UNITED STATES PATENT OFFICE

117,162

DESIGN FOR A MOTOR GENERATOR

Edward Beaton, Seattle, Wash.

Application February 13, 1939, Serial No. 82,946

Term of patent 7 years

To the Commissioner of Patents:

Be it known that I, Edward Beaton, a citizen of the United States, residing at Seattle, county of King, State of Washington, have invented a new, original, and ornamental Design for Motor Generators, of which the following is a specification, reference being had to the accompanying drawing, forming part thereof.

Figure 1 is an end elevation on a reduced scale; Figure 2 is a perspective view, and Figure 3 is a side elevation of a motor generator, showing my new design.

I claim:

The ornamental design for a motor generator, as shown.

EDWARD BEATON.
